UNITED STATES PATENT OFFICE.

LINCOLN G. SMITH, OF DES MOINES, IOWA.

BOILER-FURNACE.

1,351,802.

Specification of Letters Patent.

Patented Sept. 7, 1920.

Application filed February 3, 1919. Serial No. 274,799.

To all whom it may concern:

Be it known that I, LINCOLN G. SMITH, a citizen of the United States, and a resident of Des Moines, in the county of Polk and 5 State of Iowa, have invented a certain new and useful Boiler-Furnace, of which the following is a specification.

The object of my invention is to provide a boiler furnace of simple, durable and inexpensive construction.

More particularly it is my object to provide a boiler furnace having parts so arranged as to secure a maximum utilization of the heat.

15 A further object is to provide a boiler furnace of the type in which the air for combustion is directed through or over heated ashes and the like for preheating before being delivered to the products of combustion.

20 A further object is to provide such a furnace having simple and effective means for feeding the furnace and for discharging the ashes and waste matter therefrom.

25 With these and other objects in view my invention consists in the construction, arrangement and combination of the various parts of the device, whereby the objects contemplated are attained, as hereinafter more 30 fully set forth, pointed out in my claims and illustrated in the accompanying drawings, in which:

Figure 1 shows a vertical, sectional view through a furnace embodying my invention; 35 and

Fig. 2 shows a vertical, sectional view taken on the line 2—2 of Fig. 1.

In the accompanying drawings I have used the reference numeral 10 to indicate 40 generally the foundation or base of the furnace which has the furnace wall or inclosure 11.

45 Mounted at the upper part of the furnace inclosure is a boiler 12 having tubes 13 extending through it.

Below the forward portion of the boiler is the combustion chamber 14, having the grate 15, the supporting members 16 and 17, and an upwardly and rearwardly inclined 50 back wall 18.

The supporting wall 17 of the combustion chamber is located rearwardly of the front wall of the furnace inclosure as clearly illustrated in Fig. 1.

55 Communicating with the lower part of the boiler at the rear end thereof is a water

conducting tube 19 extending rearwardly through the rear wall of the furnace inclosure, and thence downwardly and communicating with a large transverse pipe 20. 60 Extending forwardly from the transverse pipe 20 is a series of pipes 21 placed below the boiler and extending entirely through the furnace inclosure and communicating at their forward ends with another transverse 65 pipe 22.

Extending upwardly from the pipe 22 is a pipe 23 communicating with the upper half of the boiler 12.

Communicating with the tubes 13 of the 70 boiler at the forward end thereof is a stack 24. Located rearwardly of the furnace inclosure is a hopper 25 which communicates with a feeding tube 26 extending forwardly through the rear wall of the furnace inclosure and through the back wall 18 to position for discharging fuel to the upper rear part of the combustion chamber.

In the bottom of the hopper 25 and extending into the tube 26 is a spiral conveyer 80 27 used for feeding fuel from the hopper through the tube 26 to the combustion chamber. The spiral conveyer is mounted on a shaft 28, on the outer end of which is a gearing device 29 by means of which rotation 85 may be imparted to the conveyer.

One of the side walls of the furnace inclosure is provided with a clean-out and draft opening 30 below the grate 15.

At the lower part of the front wall of the 90 furnace inclosure is an air supply and clean-out opening 31 for which a closure member 32 is provided.

Below the space formed between the walls 17 and the forward wall of the furnace inclosure is an adjustable grate or the like 33 95 below which is an ash pit 34. Above the ash pit 34 is a hinged clean-out door 35, located in front of the furnace, as shown, but which may be located wherever desired for convenience in cleaning out the ash pit.

The furnace inclosure wall at the side thereof is also provided with a clean-out opening 36 rearwardly of the supporting wall 16.

Above the pipes 21 is a fire roof or partition 37 extending from the back of the furnace inclosure forwardly to a point terminating short of the forward end of the top of the combustion chamber.

110 At the rear end of the fire roof or partition 37 is a hinged door 38, the purpose of

which will be hereinafter more fully explained.

In the practical use of my improved furnace, the fuel is supplied to the grate 15 5 through the pipe or tube 26 from the hopper 25 by means of the spiral conveyer 27.

As the fuel is supplied, the ashes and burned products are pushed forwardly off the grate into the lower part of the compartment formed between the wall 17 and the 10 forward wall of the furnace inclosure, and such ashes and the like will drop on to the grate 33.

Air is admitted through the opening 31 15 and will pass through or over the hot ashes and clinkers 39 and be pre-heated before being furnished to the upwardly moving current of heated gases and products of combustion, as such current passes upwardly, 20 as indicated by the arrow 40, around the front end of the fire roof 37.

The heated gases pass thence rearwardly and into the rear ends of the tubes 13 and thence through the boiler to the stack.

25 Air for the grate is supplied through the opening 30.

It will be seen that air is furnished to the burning fuel at the bottom of the combustion chamber, and that pre-heated air 30 is supplied to the upwardly moving current of products of combustion at the proper points to effect complete combustion and make my device act as a smoke consumer.

It will be seen that the water in the pipes 35 21 will be thoroughly heated so as to maintain a proper degree of circulation in the boiler.

Water may be supplied to the boiler through the pipe 22 and taken off in the 40 form of steam in any ordinary way.

My furnace is of very simple and inexpensive construction, and yet affords a complete control of the fuel and ashes and supplies the fresh air in such a way as to secure 45 maximum combustion.

Water is heated in the tubes 21 and the boiler is heated not only over its entire length below the boiler, but also from the tubes in the ordinary way, whereby the water in the boiler may be turned into steam with a minimum use of fuel with a maximum utilization of the heat from the fuel.

The chamber back of the back wall 18 is heated so that the coal is heated to a substantial degree before being discharged into the combustion chamber. The arrangement of the fire roof 37, where it projects over the combustion chamber forms a pocket for the incoming coal for heating and coking 55 said coal and some of the gas from the coal is drawn forwardly and burned in the forward part of said combustion chamber before the coal is moved on to the live coals above the grate 15. This results in a more

complete utilization of all the products of combustion in the coal.

The pipes 21 support and protect the fire roof 37 and this is an important feature of my invention.

When the tubes or flues 13 are cleaned the 70 door 38 may be opened and the soot and dirt dropped through the fire roof 37 to the compartment below, from whence such soot and so forth may be removed through the door 36.

75 Some changes may be made in the construction and arrangement of the parts of my device without departing from the essential features and purposes thereof, and it is my intention to cover by my claims any 80 modified forms of structure or use of mechanical equivalents which may be reasonably included within their scope.

I claim as my invention:

1. In a boiler furnace, a furnace inclosure, 85 a tubular boiler member mounted in the upper portion thereof, a substantially horizontally disposed fire wall extended across the inclosure in position spaced below the boiler member with its front edge spaced 90 rearwardly from the front wall of the inclosure, spaced transverse walls disposed below said fire wall, a grate extended between and supported on said transverse walls in position spaced below the fire wall, 95 a closure partition extended from the rear grate supporting wall to said fire wall, said partition being spaced rearwardly from the front edge of the fire wall thereby forming a pocket and means for forcing fuel through 100 said partition out on to the grate, whereby gas formed in the pocket below the fire wall must escape around the front edge of the fire wall where it will be exposed to the flames from the burning fuel on the grate. 105

2. In a boiler furnace, a furnace inclosure, a boiler disposed therein adjacent to the upper portion thereof, a substantially horizontal fire wall extended from the rear wall of the inclosure to position spaced rearwardly 110 from the front wall of the inclosure, said fire wall being spaced downwardly from the boiler, a grate disposed below the forward edge of the fire wall, a partition member extended upwardly from the rear end of said grate, whereby a gas receiving pocket is formed below the forward portion of said fire wall, a second grate disposed within said furnace inclosure below and forwardly relative to the first described grate, 115 an air inlet disposed adjacent to the second described grate in such position that the air passing therethrough may be heated by the material on said grate, and means for forcing fuel through said partition on to 120 said first described grate, whereby gas formed in the gas pocket below the fire wall from the heat of combustion will be 125

exposed to the flames from the burning fuel at the forward end of the first described grate, as said gas escapes from said pocket, and whereby the air entering said inlet will

5 be heated by the ashes and cinders pushed from the first described grate to the second described grate before coming in contact

with the flames from the burning fuel at substantially the same time that the gas from the gas chamber comes in contact therewith. 10

Des Moines, Iowa, January 21, 1919.

LINCOLN G. SMITH.
